Term of patent 7 years

(Cl. D45—4)

FIG. 1

FIG. 2

FIG. 3

FIG. 5

FIG. 4

FIG. 6

FIG. 1 is a top plan view of the expansible link chain in contracted condition showing my new design;

FIG. 2 is a top plan view thereof in partially expanded condition, portions of the conventional connecting links being visible between the top links and shown in broken lines;

FIG. 3 is an enlarged longitudinal cross sectional view of one of the top links of the chain of FIG. 1;

FIG. 4 is an enlarged side elevational view of one of the top links of the chain of FIG. 1;

FIG. 5 is an end elevational view of the link of FIG. 4, taken from the left hand end thereof; and

FIG. 6 is an end elevational view of the link of FIG. 4, taken from the right hand end thereof.

I claim:

The ornamental design for an expansible link chain for a bracelet or the like, as shown and described.
